[57] CLAIM

The design for an identification tag for rolled sheet products, as shown and described.

DESCRIPTION

FIG. 1 is a top plan view of an identification tag for rolled sheet products showing my new design;

FIG. 2 is a rear elevational view thereof, with the clip portion shown in an alternate position;

FIG. 3 is a left side elevational view thereof, with the opposite side being a mirror image;

FIG. 4 is a top plan view thereof;

FIG. 5 is a front elevational view thereof;

FIG. 6 is a rear elevational view thereof;

FIG. 7 is a right side elevational view thereof of FIG. 1;

FIG. 8 is a rear elevational view thereof;

FIG. 9 is a front elevational view thereof;

FIG. 10 is a bottom plan view thereof;

FIG. 11 is a top plan view thereof, with the clip shown in an alternate position;

FIG. 12 is a front elevational view thereof;

FIG. 13 is a bottom plan view thereof;

FIG. 14 is a rear elevational view thereof;

FIG. 15 is a left side elevational view thereof, with the broken line showing for illustrative purposes only and forming no part of the claimed design;

FIG. 16 is an enlarged fragmentary view of a bottom portion of the clip thereof; and,

FIG. 17 is an enlarged perspective view thereof, with the broken line showing for illustrative purposes only and forming no part of the claimed design.
